[57] CLAIM

The ornamental design for the foot hold attachment, as shown and described.

DESCRIPTION

FIG. 1 is a front elevational view of the foot holder attachment showing my new design, the broken line showing of a portion of a ladder for illustrative purposes only forming no part of the claimed design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view showing a use thereof, with the broken line showing of the ladder for illustrative purposes and forming no part of the claimed design.
